UNITED STATES PATENT OFFICE

CYRUS WHITE BASSETT, OF MAPLEWOOD, NEW JERSEY, ASSIGNOR TO ELEVATOR SUPPLIES COMPANY, INC., OF HOBOKEN, NEW JERSEY, A CORPORATION OF NEW JERSEY

ELEVATOR DISPATCHING SYSTEM

Application filed September 9, 1925. Serial No. 55,249.

This invention relates to elevator dispatching systems and particularly to a system in which a timing device is used, so that elevators may be given starting signals automatically.

The object of this invention is to provide a single dispatching device under the control of the dispatcher, which may be arranged to control the starting signals for any number 10 of cars.

A feature of this device is the arrangement whereby any number of cars may be dispatched automatically from the ground floor at predetermined intervals, which intervals 15 may be varied at will.

Another feature lies in the provision of means for dispatching any or all of the cars from the top floor at predetermined independently variable intervals. A further feature resides in that indications of the condition of the car starting signals are also given at the dispatcher's desk.

A still further feature is the division of the interval for a complete up and down trip 25 into either equal up and equal down trips or longer up than down trip, and vice versa; and this feature may be accomplished by keeping the complete trip time constant, or it may be varied to any desired value.

These features, together with the particular adjustment features in the device itself, will become more apparent when taken in connection with the accompanying drawings where- 30 in.

Fig. 1 represents the complete equipment mounted at a dispatching position for controlling the dispatching of a bank of cars;

Fig. 2 is a front view of the dispatcher's unit, partly in section, to show the frictional mounting of the discs;

Fig. 3 is a side view of the unit;

Fig. 4 is an end view of the unit with the slider and handle shown in section; and

Fig. 5 is a schematic arrangement of the 45 circuits involved.

One embodiment of the invention, as set forth in the drawings, consists preferably of a dispatcher's position or board from which two signals may be given in each car, one for the car to start from the ground floor and one

for the car to start from the top floor. In order to indicate to the dispatcher the condition of the signals of each car, there is provided at his position a series of signals actuated simultaneously with the car signals. There is further provided a position indicator so that the location of each car may be ascertained.

By means of this invention it is possible to operate the starting signals automatically and to regulate the interval between the starting of all the cars from the ground floor or top floor. Furthermore the schedule speed of the cars may be determined, and the length of time consumed in a round trip may be either evenly divided between the up and down trips or a larger portion may be allotted to one or the other as desired.

Any number of cars may be so controlled and others be put into service or taken out of service and the starting intervals properly adjusted.

In Fig. 1 a motor 1, whose speed may be set at any desired constant value by means of a rheostat 2 in its field or armature circuit, is suitably coupled at 3 to reduction gears, having any desired ratio, enclosed in housing 4.

The shaft 5 of the reducing gears carries one of a pair of bevelled gears 6 which drives by means of the other bevelled gear 7 a shaft 8. The latter is rotatably mounted in suitable bearings 9 and 10 carried by supports 72 and 73, which are secured to a mounting panel by means of bolts and nuts 74 and 75. The bearings 9 and 10 permit shaft 8 to be longitudinally slidable so that it may be disengaged from driving gear 6 by lifting handle 11, whose cam-like surface 12 engages the rounded concave tip 13 of shaft 8. The latter is held in its raised position, since its tip 13 is seated in a concave portion 14 at the extremity of cam surface 12. The rotation of shaft 8 may thus be stopped while its driving means continues to revolve.

Suitably keyed to shaft 8 at regular intervals are flanges 15, the number of flanges corresponding to the number of cars in the bank. Frictionally mounted on the shaft and adjacent the flanges are discs such as 16 and 17, the former having wider diameters than the

latter. Special springs 102 around the shaft tend to maintain the flange 15 and the two discs 16 and 17 in engagement, so that they will all rotate with the shaft in the same relative position in which they have previously been placed. In the surface of each disc is mounted a pin 28, projecting far enough beyond the surface to actuate one of two rows of contact buttons 40 to 45 and 46 to 51 upon each revolution of the shaft.

10 The two rows of contact buttons 40 to 51 are mounted on blocks 76 and 77 on opposite sides of shaft 8, the contact buttons on one side of the shaft being arranged in staggered relation to those on the other side.

15 Supports 72 and 73 are projected outwardly, as at 78 and 79, respectively, to hold a rod 80 in parallel relation to shaft 8. Mounted on rod 80, which may be of any desired cross section, is a slider 81 having a handle 82 and a projection 83. The latter is adapted to be moved along rod 80 and to engage any two adjacent pins, for example 28 and 29, thus aligning them.

20 25 At its lower portion there is keyed to shaft 8 at 84 a flanged wheel or drum 90, having in its outer surface a plurality of rows of indentations. A rod 91, mounted adjacent the drum 90 supported at 92, carries a slider 94 having a projection 95 to engage the indentations on drum 90 and a knurled handle 96 for easy adjustment. The first or upper row on drum 90 contains two indentations 180° apart; the second contains three indentations, 30 35 120° apart; the third, four 90° apart; the fourth, five 72° apart; and the fifth, six 60° apart. With shaft 8 disconnected from its driving gear, slider 94 may be moved along rod 91 until it is opposite any desired row on 40 wheel 90. The shaft is turned to permit projection 96 to engage each of the indentations in the row in turn, so that the relationship of the pins to each other may be accurately established.

45 45 A description of operation of the system as a whole, with the method of setting the dispatching device, will better explain the application of this invention.

50 Referring to Fig. 5, a source of power on feed wires 103 and 104 may be connected through double pole switch 52 to the field and armature of the constant speed motor 1, hereinbefore described.

55 Each of the six cars contains two lamps, one, preferably white, 53, as an up signal and the other, preferably red, 54, as a down signal. These lamps are connected at one side by means of conductor 55 to a double pole switch 56 leading to a source of current. 60 Lamps 53 and 54 at the other side are connected respectively in series with similar lamps 57 and 58, located at the despatcher's position. A double pole switch 59, also located at the dispatching position is interposed 65 between the lamps and the dispatching unit.

The contacts 40 to 45, inclusive, are connected by means of conductors 60 to 65, inclusive, to the up lamps 53 and 57, while the contacts 46 to 51, inclusive, are connected over conductors 66 to 71, inclusive, to lamps 54 and 58, so that one of these lamps will be energized every time a contact is closed.

70 Suppose it is desired to dispatch six cars at regular intervals, so that each car will consume half of its running time in going up and the other half in coming down. Handle 11 is moved upwardly, disengaging the gear 7 of shaft 8 from gear 6 on driving shaft 5. The shaft 8 will then be free to be hand rotated with its convex tip 13 seated in the concave portion of cam surface 12.

75 Slider 94 is then moved along its bar 91 until it is opposite the row on drum 90 containing six equally spaced indentations. The shaft 8 is moved by hand until the first indentation is under the projection 95. The first disc 16 is then moved until its pin 28 engages its contact 46. The shaft 8 is then moved until the next indentation in the row is in engagement with projection 95. The third disc 18 is then moved until its pin 30 engages its contact 47, and so on with the fifth, seventh, ninth and eleventh discs. Slider 81 is then moved upwardly along bar 80 until its projection 83 is directly over the first two discs 16 and 17, which, it should be noted, control the contacts for the signals of car 1.

80 The shaft is then turned so that the projection 29 of the second disc 17 is brought into alignment with that on disc 16, the former being held stationary, due to the engagement of its pin 28 with projection 46, and the latter being brought up until its pin 29 just touches projection 83. The slider 81 is then moved upwardly and the same operation is performed for each pair of contact pins. It is thus evident that all six of the up contact pins are spaced 60° apart from each other, and that all six of the down contact pins are also 60° from each other, but each up contact

ground floor, and to the dispatcher to inform him that car 1 has been signalled to start. When shaft 8 has rotated 60° , pin 31 on disc 19 strikes its contact 41 and a circuit is closed over conductor 61 for lamps 53 and 57 for car 2. Closure of contact 42, 60° later, lights the lamps for car 3, and so on similarly for the other cars. When shaft 8 has made a half revolution, pin 28 causes the closure of contact 46 and battery on conductors 105 and 106, through contact 46, over conductor 66, lights lamps 54 and 58 as a signal for car 1 to start down. The other cars are also signalled in order.

16 By proper cross connection at either switches 59 or contacts 40 to 51, inclusive, the cars may be dispatched in any desired order.

17 In large buildings during the so-called morning and evening "rush hours", best service is obtained by dividing the round trip up into unequal intervals. For example, in the morning, the up trip takes much longer than the down trip since most all the passengers are entering the building and few leaving.

22 In the evening, conditions are the reverse. Each of the large discs 16, 18, 20, 22, 24 and 26 as shown for disc 22 in Fig. 2, is calibrated, so that instead of lining up the pins as above described, they may be shifted in either direction a definite percentage with respect to their corresponding small discs 17 to 27, inclusive. It is apparent that different percentages may be fixed for different cars also if desired, since the discs are independently adjustable.

27 If, at periods of light load, only a few of the cars are in operation, the switches 59 for the cars out of service are opened and the discs for the remaining cars set to give closures at regular intervals. This is accomplished by moving slider 44 up along drum 90 to the row containing the number of indentations equal to the number of cars in service, and then setting the discs in the manner set forth above. 45 The discs for the cars cut out will merely rotate idly, since the signal circuits are open at switches 59.

32 If desired, various additional and supplemental signals and indications may be given by merely adding more contacts and pins to the discs and more signals or indicators to the car. For example, by placing pins at the proper intervals, each making a separate contact, a light with the number 5 associated therewith could be illuminated when the car was due at the fifth floor, a light with number 10 when due at the tenth floor, number 15 light when due at the fifteenth and so forth. Instead of numerals, various colors may be used. In this way the operator can exercise extremely intelligent control over his car; and the necessity of continual communication with the starter either through starter's signals or telephonic announcements, 43 is avoided.

Other embodiments may readily suggest themselves to those skilled in the art and the invention is not to be limited to the disclosure herein but is appropriately set forth in the appended claims.

What I claim as new is—

1. In a circuit controller, the combination of a shaft, means to rotate said shaft at different constant speeds, a plurality of discs mounted on said shaft, pins projecting from said discs, contacts arranged to be closed under the control of said pins, and means for regulating the position of said pins relative to said contacts, comprising an index wheel mounted on said shaft and having rows of equally spaced indentations and means whereby adjacent pins may be aligned in a desired position.

2. In a circuit controller, a rotatable element, a pair of circuit makers arranged on diametrically opposite sides of said rotatable element and in staggered relation to each other, a flange keyed on said rotatable element, a disc frictionally engaging said flange, a second disc frictionally engaging said first mentioned disc under the control of a spring, means comprising pins carried by said discs and projecting therefrom for actuating said circuit makers, and means to adjust the relative angular location of said discs.

3. In a circuit controller, a rotatable element, a pair of circuit makers arranged on diametrically opposite sides of said rotatable element and in staggered relation to each other, a flange keyed on said rotatable element, a disc in frictional engagement with the flange, a second disc frictionally engaging said first mentioned disc under the control of a spring, means comprising pins carried by said discs and projecting therefrom for actuating said circuit makers, a rod, a slider on said rod, and a drum having a series of indentations for adjusting the relative angular location of the said discs.

4. In a circuit controller, a rotatable element, a pair of circuit makers arranged on diametrically opposite sides and in staggered relation to each other, a flange keyed on said rotatable element, a disc in frictional engagement with the flange, a second disc frictionally engaging said first mentioned disc under the control of a spring, means comprising pins carried by said discs and projecting therefrom for actuating said circuit makers, a drum having a series of rows of equally spaced indentations mounted on said rotatable element and revolving therewith, a pin sliding on a rod and adapted to engage any one of said indentations, a second rod extending parallel to said rotatable element, a slider thereon for engaging any two adjacent pins whereby said pins may be properly aligned.

5. In a circuit controller, a rotating shaft, means for driving the shaft at any desired constant speed, means for connecting and dis-

connecting the shaft and driving means, a plurality of discs frictionally engaging flanges rigidly mounted on the shaft, an equal number of discs frictionally mounted on said shaft, each of said last-mentioned discs being adjacent one of said first-mentioned discs and held in frictional engagement therewith under spring tension, thereby permitting relative angular adjustment of the discs.

6. In a circuit controller, a rotating shaft, discs mounted on said shaft, pins projecting from said discs, and contacts arranged in two diametrically opposite rows about the shaft in the path of said pins, means for adjusting the relative angular position of the discs, and means for aligning any pair of adjacent pins, said means comprising a bar, a flat member slidable thereon, said bar and member being mounted at such radial distance from the shaft that the member acts as a stop for the pins upon rotation of the shaft.

7. In a circuit controller, a rotatable shaft, discs on the shaft, pins projecting from the discs, a rod mounted parallel to and above the shaft, a sliding member extending below the rod and movable thereon, said member being positioned a distance above the discs so as to contact with a desired pair of adjacent pins upon the rotation of the shaft.

8. In a circuit controller, a shaft slidably mounted in bearings, a motor for rotating the shaft, means to disconnect the shaft from the rotating means during rotation, said means also operating to reconnect the shaft to said rotating means when desired, means for effecting engagement between said shaft and associated members at successive intervals of time, comprising a plurality of discs mounted on said shaft and means for adjusting the positions of the respective discs on said shaft.

9. In a circuit controller, a shaft slidably mounted in bearings, a motor for rotating the shaft, means to disconnect the shaft from the rotating means during rotation, said means also operating to reconnect the shaft to said rotating means when desired, means for effecting engagement between said shaft and associated members at successive intervals of time, comprising a plurality of discs mounted on said shaft, means for adjusting the positions of the respective discs on said shaft, a secondary shaft driven by said first-named shaft, a bevel gear upon the secondary shaft, a bevel gear on the rotating shaft co-acting therewith, a projection on the rotating shaft extending beyond the gears and having a rounded head, means co-acting with the projection to disconnect and reconnect the bevel gears during rotation, and means to adjust the position of the discs on the rotating shaft.

Signed at Hoboken, N. J., this 3rd day of September 1925.

CYRUS W. BASSETT.
